(No Model.)

C. SCHMIDT.

CUTTING APPARATUS FOR HARVESTERS.

No. 337,625.

Patented Mar. 9, 1886.

UNITED STATES PATENT OFFICE.

CHRISTIAN SCHMIDT, OF BLUE ISLAND, ILLINOIS, ASSIGNOR OF ONE-FOURTH
TO JOHN ENGELHARDT, OF SAME PLACE.

CUTTING APPARATUS FOR HARVESTERS.

SPECIFICATION forming part of Letters Patent No. 337,625, dated March 9, 1886.

Application filed April 6, 1885. Serial No. 161,327. (No model.)

To all whom it may concern:

Be it known that I, CHRISTIAN SCHMIDT, a citizen of the United States, and a resident of Blue Island, in the county of Cook and State 5 of Illinois, have invented certain new and useful Improvements in Cutting Apparatus for Harvesters; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a top view of my improved 15 sickle-bar. Fig. 2 is a vertical section on line $x\ x$, Fig. 1. Fig. 3 is a horizontal section on line $y\ y$, Fig. 2; and Fig. 4 is a vertical cross-section on line $z\ z$, Figs. 1, 2, and 3.

Similar letters of reference indicate corresponding parts in all the figures.

My invention has relation to sickle-bars; and it consists in the improved construction and combination of parts of a sickle-bar having removable cutter-blades, as hereinafter 25 more fully described and claimed.

In the accompanying drawings, the letter A indicates a flat bar which forms the lower half of the sickle-bar, and B indicates the bar which forms the upper half, which bars are 30 secured together by means of rivets or screws C, and the upper side of the lower bar, A, is cut away to form a longitudinal recess, D, in the sickle-bar, opening in the front side of the bar and closed at the rear side and at the ends 35 of the bar.

The inner end of the top bar, B, is provided with two upwardly-projecting flanges, E, projecting from the side edges of the end of the bar, and the inner sides of these flanges are 40 beveled, and a flat block, F, having beveled side edges, G G, fits between the said flanges, and is provided with an eye, H, to which the pitman is pivoted. The upper side of this block is provided with a transverse recess, I, 45 into which a transverse bar, J, fits, having its ends resting in notches K K in the upper edges of the flanges E, which register with the ends of the transverse recess, and a screw, L, passes through the transverse bar into the block and

into the upper bar, B, securing the transverse 50 bar to the block and preventing the block from sliding in the recess formed by the flanges.

The longitudinal recess in the sickle-bar is provided with a number of shouldered pins, M, which project from the inner face of the 55 recess of the lower bar, and fit with their reduced ends N in perforations O in the upper bar, and the cutter-blades P are formed at their inner ends with L-shaped slots Q, opening at the inner edges of the blades, which 60 slots may be slipped so as to fit upon the pins which will rest in the inner ends of the slots, the inner arms of the slots being parallel with the inner edges of the blades. The innermost blade has the knee or bent portion of the slot 65 resting against the shouldered pin, and has a notch, R, in its inner edge, which notch will register with a vertical perforation, S, passing through the entire bar, and through the block having the pitman-eye, and a screw, T, 70 passes through this perforation and through the notch in the blade, securing the blade from slipping out of the recess, the blade being forced with the notch against the screw by means of a screw, U, fitting in a threaded perforation, V, in the end of the sickle-bar, which 75 screw will bear with its inner end against the outer edge of the outermost blade and force it and the intermediate blades inward, so as to force the innermost blade, with its notch, 80 against the screw T. In this manner it will be seen that by removing screw T and loosening the end screw, U, the innermost blade may be taken out, when the other blades may be slid inward upon the inner arms of their L- 85 shaped slots, and any one of the blades may now be removed for the purpose of sharpening it or replacing it with another, or for any other purpose.

When the innermost blade is inserted and 90 the screw T inserted and the tightening-screw at the end of the bar tightened, the blades will all be securely fastened in the recess of the sickle-bar, and cannot be removed excepting by removing the innermost blade.

Having thus described my invention, I claim and desire to secure by Letters Patent of the 95 United States—

1. The combination of a sickle-bar having a longitudinal recess opening in its forward side and provided with a number of vertical pins, cutter-blades having L-shaped slots 5 opening in their inner edges and fitting and sliding upon the said pins, the innermost cutter-blade having the notch in its inner side edge, the screw passing through the sickle-bar at its inner end fitting in the notch, and the 10 tightening-screw at the outer end of the sickle-bar bearing with its inner end against the outer edge of the outermost cutter-blade, as and for the purpose shown and set forth.
2. The combination of the sickle-bar having 15 the flanges upon the edges of its inner end, having beveled inner sides, the block having

the pitman-eye, and having the transverse recess in its upper side, and having beveled side edges fitting in the beveled flanges, the transverse bar fitting in the transverse recess 20 in the block and with its ends in notches in the upper edges of the flanges, and the screw passing through the transverse bar, through the block, and into the sickle-bar, as and for the purpose shown and set forth. 25

In testimony that I claim the foregoing as my own I have hereunto affixed my signature in presence of two witnesses.

CHRISTIAN SCHMIDT.
